ARTHUR S. BILLINGS, OF NORTH VANCOUVER, BRITISH COLUMBIA, CANADA.

WOOD-TRIMMER.

1,137,453.

Specification of Letters Patent. Patented Apr. 27, 1915.

Application filed July 13, 1914. Serial No. 850,771.

To all whom it may concern:

Be it known that I, ARTHUR S. BILLINGS, a citizen of the Dominion of Canada, residing at North Vancouver, in the Province 5 of British Columbia, Canada, have invented certain new and useful Improvements in Wood-Trimmers, of which the following is a specification.

This invention relates to a wood trimmer 10 of that class which is used to cut the ends of stock to any convenient angle by a slidable knife operated by a lever.

It is intended for builder's use to trim the ends of wood work where they fit together.

The trimmer, which is the subject of this application, is designed to be mounted on a trestle or bench and afford an ample bearing for the stock against which it may 20 be held during the cut. A trimming knife is provided at each end of the base frame, which knife is slidable within an open frame slideway having provision for angling it in relation to the fence against which the work 25 is held. Provision is made for the adjustment of the pivots of the slideway that the knives may cut true to the axis on which their slideway frames are angled. The device is designed throughout to enable satisfactory work to be done on it.

The invention comprises various subsidiary features of design to which attention will be drawn in the following specification, which specification fully describes the device, reference being made to the drawings 35 by which it is accompanied, in which:

Figure 1 is an elevation looking on the face of the fence, one end knife and its angling slideway being removed. Fig. 2 40 is a plan of the same. Fig. 3 is an end elevation looking on the knife frame and its slideway. Fig. 4 is an enlarged detail of the adjustable stop of the frame. Fig. 5 is a sectional plan of a portion of the knife 45 frame showing the manner of adjustment of the blade thereto, and Fig. 6 shows in perspective a supplementary provision enabling the device to be used for cutting shouldered tenons.

The device comprises a base or bed member 2 having a fence member 3 at right angles to it, which parts may be integral or secured to one another. They are of sufficient length to afford ample support for the 50 stock, the ends of which are to be trimmed,

and are of cast iron or other suitable metal and are webbed to afford the required strength with a minimum of weight. At each end the depth of the back fence 3 is increased upward and is provided with an 60 upper and lower bearing 4 and 5 for the reception of the pivot bearings of the open rectangular slideway 6 in which the knife holding frame is endwise movable to and from the axis of the pivot of the knife 65 frame.

The upper surface of the bed 2 on which the stock is placed terminates at each end at an angle of forty-five degrees from the back fence 3 and the shoulder has a facing 70 strip 8 against which the swinging slideway frame is checked at the forty-five degree angle. Below this surface of the bed plate an arc-like segment 7 endwise projects, the curve of which arc is struck from the 75 axis of the pivot. This segment 7 affords a support for the outer ends of the swinging frame 6 and that slideway may be clamped to it at any desired angle in a manner to be described.

The knife frame slideway 6 is an open rectangular frame, the upper and lower members of which have a groove at 9 for the reception of the reciprocating knife frame. To afford facility of adjustment of 80 the axis of the pivots of the slideway to the plane of the cut of the knife, the pivots 10 are not one with the slideway but each projects from a separate member 11 which is adjustably secured in the upper and lower 85 side of the slideway frame 6. Each member 11 is secured by two set screws 12 which pass through apertures in the member 11 and are threaded into the frame 6. The apertures for the set screws are slightly 90 elongated across the plane of the knife frame and on the opposite side of the pivot pin 10 a small bolt or screw 13 passes through a lug forming part of 11 and through or threaded into a lug 14 forming a part of the 95 frame 6. By this means the screws 12 being slackened, the bolt or screw 13 may be tightened up or slackened out and the axis of each pivot pin may thus be adjusted to the 100 cutting plane of the knife.

A knife frame 17 is endwise movable in the grooves 9 of the swinging slideway 6 and to the angled inner end of this frame 17 a knife blade 15 of parallel width and thickness is secured by screws 16. The 110

screws 16 pass through holes in the knife frame which are elongated in the direction of movement of the knife and are seated in apertures in blade 15, thus permitting adjustment of the knife blade.

The seat for the knife blade on the inner face of its frame 17, see Fig. 5, is slightly angled from the plane of movement of the cutting edge of the knife so that with a 10 blade of uniform thickness the face of the blade will have the required clearance from the plane of the cut to avoid friction of the blade on the cut face of the wood.

The knife holding frame 17 with its blade 15 is endwise reciprocated in the slideway 6 by a gear wheel 18, the teeth of which mesh below with the teeth 20 of a rack formed in the lower part of the slideway 6, and above with the teeth of a similar rack 21 downwardly projecting from a web outwardly projecting from the upper part of the knife frame 17.

The gear wheel 18 is rotated to reciprocate the knife frame by a handle lever 22, the 25 end of which fits with a slightly endwise taper and edge dovetail between projections 23 formed on the outer face of the wheel. This lever is secured to the wheel by a screw 19 through its center and a retaining guard 30 plate 24 secured to the knife frame 17 and extending along its rack 21.

The knife frame slideway 6 is secured at any desired angle on the arc segment 7 of the base frame by a clamp lever 25 which is 35 pivotally mounted between lugs 26 downwardly projecting from the underside of the slideway frame 6 adjacent to the outer edge of the arc 7. The shorter end of this lever is shaped to engage the underside of the arc 7, 40 and on the end of the longer arm of the lever bears the end of a rod 27, which passes rotatably through the upper part of the frame 6 and is threaded at its lower end through the lower portion of the slideway frame. 45 The upper end is provided with a knurled head by which the screwed rod may be rotated to clamp or release the slideway frame 6 to the arc 7 of the base. Adjacent to the pivots of the swinging slideway 6 a guard member 29 projects backward from the fence member beyond the extreme movement of the knife and is similarly angled.

An adjustable stop is mounted on the fence 3, which, when not required, may be 55 swung clear of the stock seat on the bed 2. The edge of the web 30 along the upper edge of the fence 3 is machined to offer a slightly dovetailed cross section and on this dovetailed edge is slidably mounted a member 31. 60 Between the upper and lower engaging portions of this member 31 is a slit 32 which renders it sufficiently resilient that the two parts may be clamped together on the web by a screw 33 rotatable in the upper part 65 and threaded in the lower part, that is, in

the part below the saw cut 32. On this member 31 is pivotally mounted at 34 the jaw of a stop member 35 which is L shaped that it may extend down the acting face of the fence 3 where it will form a stop to determine the length of any stock to be cut, or when not required may be swung back clear of the acting face, as shown in dot and dash lines in Fig. 3. This stop may be moved to and secured at any desired position along the 75 fence 3, which may be graduated if thought desirable in inches and fractions.

With a trimmer so constructed the stock to be cut is afforded an ample support on the length of the bed 2 and its frame 3 to 80 hold it securely under the pressure of the cut, and the cut will, therefore, be true to the bearing faces of the stock. A knife blade being mounted at each end enables either end to be cut, and if the stock is longer than the 85 bed frame it may be introduced through the opening of one slideway frame to be acted on by the knife of the other. If the stock to be cut is shorter than the distance between the knives, each knife slideway 6 may be 90 clamped to an angle required and one stop 35 may be set to determine the length to which one end of a number of pieces of the same length should be cut and the other to determine the cut of the other end to give 95 the exact length required, one stop being swung clear while the other is in use. To enable a square shouldered tenon to be cut on this device, blocks 36 may be furnished with it which are angled to the angle of the 100 knife edge, each block having a pin or pins 37 to fit into apertures 39 provided in the fence. Each block has a ledge 38 on which the lower corner of the stock will rest. This ledge affords the stock a positive support and 105 avoids the inaccuracy due to an injured or imperfect corner on the stock consequent on allowing the lower corner of the stock to rest on the bed plate 2, as is the common practice. Provision may be made at 40 for securing the 110 device to a bench or trestle.

Attention is directed to the following advantageous features in the design of this device: The bed and fence being of ample length and provided with an open frame 115 knife slideway at each end, enables the stock to be amply supported in relation to the plane of the cut; and with the use of a knife at each end and with stops which are readily adjustable and susceptible of being swung 120 into or out of use without removal from the fence enables a quantity of short stock to be duplicated without readjustment: The provision by which the pivots of each swinging slideway may be adjusted in relation to the cutting plane of the knife insures the maintenance of accurate work under the unavoidable wear outward from the pivots to which the pivots and the knife frame bearings are exposed, and the provision of a knife seat 125 130

that is angled to afford the required face clearness of the blade is advantageous in the sharpening and renewal of the knife blades.

Having now particularly described my invention, I hereby declare that what I claim as new and desire to be protected in by Letters Patent, is:

1. In a wood trimmer having a fence and a knife slideway pivotally mounted in relation to one another, means for adjusting the axis of the pivots in relation to the plane of movement of the knife.

2. In a wood trimmer having a base plate and lengthwise fence and a knife frame slideway pivotally mounted thereto, means for adjusting the axis of the pivots of the slideway to the plane of movement of the knife frame.

3. A wood trimmer, comprising the combination with a bed plate having a lengthwise fence plate integral with or secured to it, of an open slideway frame pivotally mounted at each end on an axis which coincides with the plane of the fence, means for clamping each slideway frame at an angular adjustment, a knife frame having a knife blade secured to it said frame slidable in the slideway, and means for endwise reciprocating the knife frame.

4. A wood trimmer, comprising the combination with a bed plate having a fence plate at right angles to it, of an open frame pivotally mounted at each end to move on an axis which coincides with the plane of the fence, said frame having a grooved slideway, means for adjusting the axis of the pivots in relation to the plane of the slideway, means for clamping the slideway frame, and a lever operated knife frame movable in the slideway of each frame.

5. A wood trimmer, comprising the combination with a bed plate having a lengthwise fence plate at right angles to it, an open slideway frame pivotally mounted at each end to move on a vertical axis, a knife frame endwise movable in each slideway said knife frame having a seat for the knife blade the plane of which seat is angled slightly to the plane of movement of the knife frame, a knife blade of uniform thickness adjustably secured on the seat, and means for endwise moving each knife frame in its slideway.

6. In a wood trimmer, a bed plate having a lengthwise fence plate at right angles to it, said fence plate having a rearwardly projecting flange at its upper edge, a stop comprising an attaching clamp member slidably adjustably secured on said flange, an L-shaped stop member pivotally mounted on

said securing member and susceptible of being moved to project down the fence and lie against the front face of the same or of being swung up and back, all being arranged substantially as shown and described.

65

7. In a wood trimmer having a bed plate with a cutting knife slideway frame pivotally mounted at each end, means for securing each slideway frame in any desired angular adjustment, said means comprising a lever mounted between lugs downwardly projecting from the slideway frame adjacent to an arc extension from the end of the base plate the shorter end of said lever being shaped to engage the underside of the arc and the longer end of the lever produced under the end of a screw threaded through the slideway frame.

75

8. A wood trimmer, comprising the combination with a bed plate having a lengthwise fence plate at right angles to it said fence plate having pivotal bearings at each end for an open slideway frame and the end of the base plate at each end at an angle of forty-five degrees from the pivot bearings being dropped below the plane of the bed plate and therefrom produced in a segment of a circle struck from the axis of the pivot bearing, an open slideway frame having adjustable pivots to fit the bearings at the end of the fence, and rack teeth upwardly projecting from its lower side, means for securing this slideway frame in any desired position of angular adjustment, said means comprising a lever pivotally connected to the underside of the slideway frame adjacent to the outside of the segmental projection of the base plate, said lever being formed at one end to engage the underside of the arc and a screw thread-

80

90

means comprising a lever pivotally connected to the underside of the slideway frame the end of which screw bears on the other end of the clamping member, a knife frame endwise movable in grooves of the slideway said knife frame angled at its inner end and having a knife blade secured to its angled end, said knife frame having also rack teeth downwardly projecting from its upper outer side, a gear wheel the teeth of which mesh with those of the rack of the slideway frame 105 and with those of the knife frame, a handle lever secured on the outer face of the gear wheel and a guard plate secured to the knife frame adjacent to its rack.

100

110

In testimony whereof I affix my signature 115 in presence of two witnesses.

ARTHUR S. BILLINGS.
